UNITED STATES PATENT OFFICE.

AGUSTIN JIMÉNEZ, OF NEW YORK, N. Y.

HAT-HOLDING STAND.

Application filed July 6, 1927. Serial No. 203,813.

This invention relates to store furniture and more particularly to a stand adapted to hold a hat so that a milliner can very easily decorate or trim the hat by painting, 5 sewing or otherwise applying decorations thereto.

One object of the invention is to provide a frame so constructed that it may be vertically adjusted and also to permit a spindle 10 forming part of the device to be swung either in a horizontal or vertical plane and thereby dispose a hat carried by the frame in such position that an operator may very easily apply decorations or trimmings to 15 the hat.

Another object of the invention is to rotatably mount a hat-carrying form upon the spindle so that it may be turned while the hat is being painted or otherwise decorated 20 or trimmed and also to permit the hat-carrying form to be securely but releasably held in a set position and thereby prevent it from moving while being painted.

The invention is illustrated in the accompanying drawing, wherein

Figure 1 is a view showing the improved hat holder partially in side elevation and partially in section;

Fig. 2 is a sectional view taken on the 30 line 2—2 of Fig. 1 and showing the hat-carrying form in end elevation;

Fig. 3 is an enlarged fragmentary view of the connection between a spindle and staff forming part of the hat holder.

The hat holder includes a stand having a 35 base 1 provided with supporting feet 2 and carrying a standard 3. The standard consists of a tube of suitable length and has its lower end threaded or otherwise connected 40 with the base 1. A staff 4 is slidably and rotatably received in the tubular standard 3 and adjacent its upper end the standard is formed with a transversely extending 45 threaded opening 5 through which a set screw 6 passes to engage the staff and securely but releasably retain the staff in a set position. It will thus be seen that the staff 50 may be vertically adjusted and may also be turned in the standard and the set screw then tightened to retain it in a set position. The upper end portion of the staff is flattened and perforated to form an eye 7, a side 55 face of which has flat contacting engagement with a side face of a similar eye 8 formed at the inner end of a spindle 9. A

bolt 10 which constitutes a pivot for the spindle passes through aligned openings in the eyes 7 and 8 and carries a wing nut 11 which, when tightened, will cause the spindle to be securely held in a set position. 60 When the nut 11 is loosened, the spindle may be swung vertically about the bolt 10. Therefore, the spindle may be adjusted by vertical swinging movement and securely held in a position which will be convenient 65 to the operator when the nut is again tightened.

In order to carry the hat which is to be painted or trimmed, I have provided a hat-carrying form 12 which may be formed of 70 wood or any other desired material. The form, which is hollow as clearly shown in Figs. 1 and 2, is open at its inner end but has its outer end closed by a hemispherical head. It will thus be seen that the hat-carrying 75 form resembles a dome and is to be disposed within a hat. It will, of course, be obvious that the hats must fit rather tightly upon the carrier and, therefore, a number of carriers of various sizes must be provided and 80 the proper carrier employed according to the size of hat to be decorated. Cross bars 13 and 14 extend diametrically through the carrier and are secured to the walls thereof in spaced relation to each other, as shown 85 in Fig. 1. Openings 15 are formed in the cross bars axially of the carrier, and these openings are intended to receive the spindle so that the carrier may be rotated about the spindle and thereby allow any portion of a 90 hat placed upon the carrier to be so disposed with respect to the operator that the decorations or trimmings may be readily applied thereto. The outer cross bar 14 bears against a cotter key 16 passed transversely through the spindle and a securing nut 17 which is threaded upon the free end of the spindle is adapted to engage the cross bar 13 when 95 tightened and thereby cause pressure to be applied to the cross bars which will securely 100 but releasably retain the hat carrier against rotation upon the spindle. It will thus be seen that when the nut 17 is tightened the hat carrier will be firmly held in a set position and will not be liable to turn while 105 an operator is painting flowers or the like upon a hat. It will also be noted that by loosening the nut so that the hat carrier may rotate about its spindle a stenciling strip may be disposed about a hat upon the car- 110

rier and decoration very easily stenciled upon a hat. I have, therefore, provided a hat holder which may be adjusted vertically and horizontally according to the wishes of an operator and a hat may very easily have trimming or painted decorations applied thereto.

Having thus described the invention, I claim:

- 10 1. A hat holder comprising a stand, a spindle extending from said stand and having a threaded free end portion, a form disposed about the spindle, cross bars extending transversely through said form and formed with alined openings disposed axially of the form and receiving said spindle to rotatably mount the form, an abutment carried by said spindle in spaced relation to its threaded end and engaging one cross bar, and a nut 20 screwed upon the free end of said spindle to engage the other cross bar, whereby the bars may be clamped between the nut and abut-

ment and releasably retain the form in a set position.

2. A hat holder comprising a stand, a 25 spindle extending from said stand and having a threaded free end portion, an abutment spaced from the free end of said spindle, a hollow form disposed about said spindle and open at its inner end and having a head at 30 its outer end, inner and outer cross bars extending diametrically through said form in spaced relation longitudinally thereof and having alined openings disposed axially of the form, said spindle being received in said 35 openings with its threaded end projecting from the inner cross bar and the outer cross bar engaging said abutment, and a securing nut upon the threaded end of said spindle to engage the inner cross bar and releasably 40 retain the form in a set position.

In testimony whereof I affix my signature.

AGUSTIN JIMÉNEZ. [L. S.]
